UNITED STATES PATENT OFFICE.

FREDERICK COWIN, OF CHICAGO, ILLINOIS.

MEAT-FLATTENER.

SPECIFICATION forming part of Letters Patent No. 661,792, dated November 13, 1900.

Application filed March 14, 1898. Serial No. 673,728. (No model.)

To all whom it may concern:

Be it known that I, FREDERICK COWIN, a subject of Her Majesty the Queen of Great Britain, and a resident of the city of Chicago, 5 in the county of Cook and State of Illinois, have invented certain new and useful Improvements in Meat-Flatteners, of which the following is a specification.

My invention relates to meat-flatteners, 10 and has been applied particularly to flattening the sides or bellies of hogs. These are received by the operator in a curved form, being in about the shape that same are taken from the hog and are usually hardened in 15 such shape through refrigeration. Heretofore they have usually been flattened with bats in the hands of the operator.

The main object of my invention is to provide a machine which will facilitate this 20 process.

Further and incidental objects are to provide a striking or flattening member on such machine which will operate without injury to the meat-block when the space between the 25 striking member and the meat-block is free and to provide for properly treating meat of different thicknesses.

I accomplish these objects by providing a machine in which the blow of the striking 30 member is similar to the blow of the bats used heretofore, in which such member is retarded at the end of its downward stroke, so as to prevent injury to the block, as above stated, and in which such member strikes a 35 yielding blow, governed by the thickness and resistance of the meat.

The construction and operation of my device will be understood from the following description by reference to the accompanying 40 drawings, in which—

Figure 1 is a front elevation of a meat-flattening machine constructed according to my invention. Fig. 2 is a horizontal section of same on the line xx of Fig. 1. Fig. 3 is an enlarged vertical central section of the pneumatic mechanism shown in Fig. 1, partly broken away and showing the interior construction in detail.

The device shown in the drawings consists 45 mainly of a meat-block 14, having rigidly secured thereon the cylinder 1 and striking member of a pneumatic drill in which a plate

6 has been substituted for the tool-point. The plate 6, which is the striking or flattening member of the device, is directly operated 55 by mechanism which is essentially the same as that used in the Sullivan pneumatic rock-drill or the Rand Drill Company's slugger rock-drill described on page 188 of Appleton's 60 *Modern Mechanism*.

In Fig. 1 the plate 6 is shown at the lower limit of its stroke, the member 4 being adjusted by the screw 7 and through the arms 4', so as to prevent the plate 6 from striking the block. A head 2, supported on springs 3, 65 intervenes between the member 4 and an inner head on the arm 5 essentially the same as in said rock-drill. The cylinder 1 is supported by the tripod 7', which is rigidly secured upon the block 14. The air-pipe 8, 70 communicating with the cylinder, is provided with a valve 9. This valve is normally closed by the spring 10. A rod 11 connects the valve to a pedal 12, whereby and through the rod 11 the valve is operated. The pedal is pivoted to the arm 12' at 12", said arm being secured to the block 14.

16 represents a bench having a cut therein for receiving the block, same being arranged so that the meat can be conveniently passed 80 from the bench to the block.

I prefer to arrange the block and parts secured thereto so that same may be readily removed from the bench when the machine is not in use, a section being provided for filling the cut in the bench, thus adapting the bench for other purposes when the machine is removed. To this end the block is mounted on rollers and a flexible tube 13 is connected with the pipe 8, the pipe 8 being braced 90 to the cylinder by the member 8'. This is so arranged only in case it is desirable to have the block movable. When the block is to remain in a fixed position, the flexible tube 13 and brace 8' may be omitted, and the pedal 95 may be supported in any suitable manner other than upon the block. The arm or piston-rod 5 is vertically slidable in the cylinder 1 and has thereon the shoulders 17 and 18. The sleeve 19 has its upper end vertically 100 slidable in the cylinder 1 and has its lower end enlarged and bearing against a gasket 20. The sleeves 21 and 22 are threaded in the member 2. The valve-casing 23 has a recip-

roating valve 24 vertically slidable therein and operated by the member 25, which is pivoted at 26 in the cylinder. The port 27 leads from the valve-easing into the upper part of the cylinder, and the port 28 leads from the valve-easing into the lower part of the cylinder. When the piston-rod 5 is at the lower end of its stroke, the valve 24 will be in the position shown and will permit the steam or air to pass through the port 28 and under the shoulder 17, thus raising the piston. When the piston is at the upper end of its stroke, the valve 24, through the action of the member 25, will be raised, so as to close the end 15 of the port 28 communicating with the valve and to open communication between the valve and the port 27. This will admit the steam or air above the shoulder 18 and will thus force the piston downwardly. The lower 20 part of the piston immediately above the shoulder 17 will bear against the face 29 of the member 25 when the piston is at the upper end of its stroke, thus opening the port 27 and closing the port 28. The screw 7 is 25 threaded into the head 30 of the cylinder and has an enlargement 31, supporting the member 4. The springs 3 act between the member 4 and the shoulder 32 of the member 2. The position of the member 4 is regulated by 30 the screw 7, and thus determines the limit of the downward stroke of the piston-rod 5. At each downward stroke the sleeve 19 will be forced downwardly in a slight degree against the action of the springs 3. When the valve 24 35 is in the position shown in Fig. 3, the chamber 33 communicates with the port 28 around the lower part of the valve 24. In this position communication between the port 27 and chamber 33 is closed, while said port 27 communicates through the valve with the exhaust-chamber 34, from which the steam passes out 40 through the exhaust-port 35.

The operation of the device is as follows: An operator stands in front of the block toward the right with one foot upon the pedal. He receives the sides of meat from the bench and pushes same under the plate 6 while opening the valve 9 by pressing upon the pedal. The air is thereby admitted to the 45 cylinder, causing the member 6 to move up and down with the stroke of the piston in the cylinder. An assistant stands at the left of the block, and as the sides of meat protrude upon that side of the member 6 he engages same with a hook or with his hands and draws same toward his side of the block, removing same upon that side. It will be seen that the meat may thus be properly flattened 55 throughout its length and width.

60 I am aware that some efforts have been made heretofore to provide a machine for this purpose, but such efforts have been mainly experimental and have produced no practical machine. The failure of such experiments has apparently been mainly due to the fact that no adequate means have been provided for cushioning and retarding the blow

of the striking or flattening member toward the end of the stroke.

I find that it is desirable to secure a hard 70 quick cushioned blow and that this end is attained by the use of pneumatic mechanism, such as is applied in the pneumatic drills hereinbefore mentioned. A yielding blow is thus obtained which is similar in effect to that of 75 the bat in the hands of the operator and is much more rapid and effective.

Through the effective cushioning of the stroke of the member 6 direct contact with the block, as well as all jarring and consequent injury to the other parts of the machine, is prevented.

Through the effective cushioning of the stroke of the member 6 direct contact with the block, as well as all jarring and consequent injury to the other parts of the machine, is prevented.

What I claim as my invention, and desire to secure by Letters Patent, is—

1. A meat-flattening machine, comprising a meat-block; a member 6 having a flat under 90 surface; and suitable mechanism secured to said block for imparting a yielding striking motion to said member and limiting the end of its downward stroke to a point above and free from the opposed surface of said block; 95 substantially as described.

2. A meat-flattening machine, comprising a meat-block; a member 6 having a flat under surface; suitable mechanism secured to said block for imparting a yielding striking motion to said member and limiting the end of its downward stroke to a point above and free from the opposed surface of said block; and a pedal connected to said mechanism whereby same can be instantly stopped and started 100 by the operator during the operation of feeding the machine; substantially as described. 105

3. A meat-flattening machine, comprising a meat-block; a member 6 having a flat under 110 surface; suitable pneumatic mechanism secured to said block for imparting a yielding striking motion to said member and limiting the end of its downward stroke to a point above and free from the opposed surface of said block; an air-feed pipe communicating 115 with said mechanism; a spring-valve in said pipe, normally closed; and a pedal connected to said valve whereby same can be instantly opened and closed by the operator during the 120 operation of feeding the machine; substantially as described.

4. A meat-flattening machine, comprising a portable roller-mounted meat-block; a member 6 having a flat under surface; suitable pneumatic mechanism secured to said block 125 for imparting a yielding striking motion to said member and limiting the end of its downward stroke to a point above and free from the opposed surface of said block; an air-feed pipe communicating with said mechanism, 130 and having a flexible section; a spring-valve in said pipe, normally closed; and a pedal connected to said valve whereby the same can be instantly opened and closed by the opera- 135

tor during the operation of feeding the machine; in combination with a bench having a part cut out for receiving the block; substantially as described.

5 5. In an apparatus for flattening and smoothing cuts of meat, a framework, a pounding-block mounted to reciprocate therein, said block having an extended plain surface, and means for reciprocating said pounding-block, in combination with a stationary block hav-

ing an extended plain flat surface arranged to coöperate with the pounding-block, as and for the purpose set forth.

Signed by me at Chicago, Illinois, this 11th day of March, 1898.

FREDERICK COWIN.
